PROTECTIVE GOGGLES

Samuel E. Bouchard, Rochester, N. Y., assignor
to Bausch & Lomb Optical Company, Rochester, N. Y., a corporation of New York

Application June 16, 1938, Serial No. 214,102

4 Claims. (Cl. 2—14)

The present invention relates to goggles and more particularly to ventilated protective goggles.

One of the objects of the present invention is to provide ventilated protective goggles which are simple and inexpensive in construction yet rugged and efficient in use. Another object is to provide goggles which are well ventilated and yet afford ample protection against both mechanical injuries and harmful radiations. A further object is to provide goggles having a simple but effective protective shield secured within each eyecup. These and other objects and advantages reside in certain novel features of construction, arrangement and combination of parts as will hereinafter be more fully set forth and pointed out in the appended claims.

Referring to the drawing:

Fig. 1 is a front elevation of a pair of goggles embodying my invention.

20 Fig. 2 is a section taken on line 2—2 of Fig. 3.

Fig. 3 is a section taken on line 3—3 of Fig. 2.

Fig. 4 is an elevation of the bridge anchoring socket.

Fig. 5 is a fragmentary side elevation of one of 25 the eyecups.

A preferred embodiment of my invention is illustrated in the drawing wherein is illustrated a pair of goggles consisting of two eyecups 10 and 11, connected by a bridge designated generally at 30 12. These goggles are retained on the head by a suitable head band 13. The two eyecups 10 and 11 are substantially identical so only one will be described.

As shown in Figs. 2 and 3, the eyecup 10 is 35 roughly cylindrical in shape. One edge of the eyecup 10 is slightly flanged outward and shaped to fit the contour of the face adjacent the eye while the other edge is a flat, lens-receiving surface. A large ventilating opening 14 is formed 40 in the temporal side of the eyecup 10 and a screen 15 secured to the eyecup by rivets 16 covers the opening 14 to prevent the entry of foreign particles. A projection 17 secured to the screen 15 extends through the opening 14 adjacent the 45 face engaging edge to secure the screen 15 rigidly to the eyecup 10. The screen 15 has a rearwardly extending lip 15' which is perforated at 18 to receive the head band 13. A suitable enlarged tip 19 prevents removal of the head band 13.

50 Within the eyecup 10 is a cylindrical inner cup 20. When it is desired to protect the eye from radiations as well as foreign particles, this inner cup may be made of a suitable opaque material such as paper or fiber, for example. Secured to 55 the inner cup 20 by rivets 21 is a clip or projection

22 which engages the edge of the opening 14 adjacent the face engaging edge of the eyecup 10. Suitable projections 23 on the inner cup 20 engage the inner wall of the eyecup 10 and hold the two cups 10 and 20 in spaced relation so as to provide an air passage between the cups.

At the nasal side, the inner cup 20 has a plate 24, preferably of metal, which is provided with an aperture 25 in alignment with an aperture 26 in the eyecup 10. A socket member 27 of cylindrical 10 form is secured in these apertures 25 and 26 and held against removal by a flange 28 at its rear end. The front end of the socket member has a keyhole-shaped opening 29 for receiving the 15 bridge member 12 which is preferably formed as a series of balls 30 connected by links 31. The large part of the opening 29 will readily pass the balls 30 while the small part will admit only the links 31 and thus hold the balls 30 against removal. The balls 30 and links 31 are preferably covered 20 with a tube 32 of soft material such as rubber.

A suitable lens 33 is mounted on the lens-receiving front edge of the eyecup 10 and engages the front edge of the inner cup 20. This front edge of the cup 20 is provided with cut away depressions 34 to permit the passage of air from the space between the two cups to the space within the inner cup 20.

In order to improve the ventilation of the goggles, the eyecup 10 is provided with a series of 30 radial apertures 38 which are located below the edge of the cap ring 37 and open into the space between the eyecup 10 and the inner cup 20. These apertures 38 are preferably small so as to 35 prevent the entrance of dirt or other particles into the eyecup 10.

The lens 33 is preferably colored to absorb any 40 glare or harmful radiation. A second lens 35 in alignment with the lens 33 and spaced therefrom by a washer 36, is preferably formed of hardened glass to protect the inner lens 33 from mechanical blows. The two lenses 33 and 35 are secured on the eyecup 10 by a cap ring 37 which is threaded onto the eyecup 10. The threaded portion of this 45 cap ring 37 extends along the side of the eyecup 10 past the large part of the opening 29 in the socket member 27 and thus serves to lock the bridge 12 in the socket member 27.

From the foregoing it will be apparent that I 50 am able to attain the objects of my invention and provide a new and improved goggle which is simple, inexpensive, rugged and efficient. The particular goggle described is particularly adapted for protection against both harmful radiation and mechanical blows and the particular lenses and 55

material of the inner cup were chosen for this purpose. For other purposes other selections could readily be made without departing from the spirit of my invention or the scope of the appended claims.

5 I claim:

1. In a pair of goggles an eyecup having one edge shaped to fit the face of the wearer and the other edge shaped to receive a lens, said eyecup having an opening through the temporal side, an inner cup adapted to fit within said eyecup in spaced relation therewith, positioning means secured on said inner cup for engaging the edge of the opening in the eyecup, said cups being provided with aligned apertures through their nasal sides, a socket member extending through said apertures, and means on said socket member for detachably retaining a bridge member.
- 10 2. In a pair of goggles an eyecup having one edge shaped to fit the wearer and the other edge shaped to receive a lens, said eyecup having an opening along the temporal side thereof, a perforated shield secured on said eyecup over said opening, an inner cup adapted to fit within said eyecup, a stop secured to said inner cup for engagement with the edge of said opening to position said inner cup in said eyecup, means on said inner cup for engaging the eyecup to hold the inner cup in spaced relation to said eyecup, said cups having aligned apertures through their nasal sides, a socket member within said apertures and means on said socket member for detachably retaining a bridge member.
- 15 3. In a pair of goggles an eyecup having one

edge shaped to fit the face of a wearer and the other edge shaped to receive a lens, said eyecup having an opening in the temporal side, a perforated screen secured to said eyecup and covering said opening, an inner cup adapted to fit within said eyecup, means on said inner cup for engaging the edge of said opening to position said inner cup, means for holding said inner cup in spaced relation to said eyecup, said cups being provided with aligned apertures in their nasal sides, a socket member in said apertures, means in said socket member for retaining a bridge member, a lens adapted to rest on the lens-receiving edge and engaging the edge of said inner member, said edge of said inner member being cut away to provide air passages, and means for securing said lens on the lens-receiving edge.

4. In a pair of goggles an eyecup having one edge shaped to fit the face of the wearer and the other edge shaped to receive a lens, said eyecup having a ventilating opening in its temporal wall, an inner cup smaller than the eyecup and positioned within said eyecup, means on said inner cup for engaging a wall of said aperture to secure the temporal side of said inner cup within said eyecup, said eyecup having an opening through its nasal wall, a socket member positioned in said opening, means on said socket member for detachably retaining a bridge member and means on said socket member engaging the nasal wall of the inner cup to retain said inner cup within said eyecup.

SAMUEL E. BOUCHARD.
